UNITED STATES PATENT OFFICE.

MELLEN FREEMONT ROBINSON, OF LITCHFIELD CORNERS, MAINE

LIQUID-MEASURING VESSEL.

SPECIFICATION forming part of Letters Patent No. 298,504, dated May 13, 1884.

Application filed January 16, 1884. (No model.)

To all whom it may concern:

Be it known that I, MELLEN FREEMONT ROBINSON, of Litchfield Corners, in the county of Kennebec, of the State of Maine, have invented a new and useful Improvement in Liquid-Measuring Vessels; and I do hereby declare the same to be described in the following specification and represented in the accompanying drawings, of which—

10 Figure 1 is a side elevation; Fig. 2, a vertical section, and Fig. 3 an under side view of a liquor-measuring can or pitcher of my improved kind. Fig. 4 represents it as applied to a jug.

15 The nature of my invention is duly defined in the claim hereinafter presented.

In the drawings, A denotes a pitcher or measuring-can having a nose or spout, a, a handle, b, and a cover, e, the latter being 20 hinged to the body of the can. From the bottom of the can, which is concavo convex, four legs, d, project downward at or near its periphery, while at the central part of the body there is an educt or tube, e, opening out of the 25 can, such educt having in its mouth of discharge a stopple, f, which is fixed to an arm, g, projecting from a slide-rod, h, at a right angle therewith. This slide-rod, arranged in the rear part of the can and extended upward through 30 the cap part i, to which the cover is hinged, is supported in bearings or eyes k k, projecting from the inner surface of the can, the said bearings being of a character to admit of the slide-rod being raised or depressed, as well as turned

35 around laterally in them, in order to effect the insertion of the stopple in or its removal from the tube, and of turning the stopple aside or from over the tube, as occasion may require. Furthermore, there are extended downward

40 from the can-bottom four auxiliary legs, l m m m, the three marked m being curved as shown, and arranged at equal distances apart, and disposed in a circle of about half the diameter of the can-bottom and concentric there-

with. The remaining leg l is shorter than 45 either of the three marked m, such leg l being to rest on the handle n of a jug, B, when the tube e may be in the mouth of the jug, and the auxiliary legs m be resting on the upper or conical part of the jug, and serving therewith 50 to centralize the tube in the said mouth, in order that there may be between them a clear annular space for the escape of air from the jug while a liquid may be running into it from the can. Beside the inner range of legs, there 55 are three ribs, r, extending from the can-bottom and from the tube to the said legs, such ribs being to rest on the top of the nose of the jug, so as to enable the air to freely pass from the nose while liquid may be running from the 60 can into the jug. The outer set of legs are longer than the inner set, and are to support the can upon a bench or table, the inner set being for a different purpose, as mentioned.

With this measuring-can a liquid can be 65 measured and poured from the spout, or may be drawn from the can through the tube e, as occasion may require, the measures being denoted by marks or grooves o made in the can at suitable altitudes above its bottom.

I do not claim a measuring-funnel provided with a discharging-nose, and a valve thereto, and having legs extending from it to support it on a flat surface. In my improved funnel I have certain auxiliary legs as well as certain 75 ribs thereto, arranged in manner and for the purposes hereinbefore described, therefore

I claim—

The measuring can or pitcher provided with a spout or nose, main and auxiliary legs, 80 a set of ribs, a discharging-tube, and a stopper thereto, arranged and adapted substantially as and for use as represented.

MELLEN FREEMONT ROBINSON.
